UNITED STATES PATENT OFFICE.

MATT M. COREY, OF CHICAGO, ILLINOIS, ASSIGNOR TO R. D. SWISHER MFG. CO., OF CHICAGO, ILLINOIS, A CORPORATION OF ILLINOIS.

LOCK FOR POCKET SEALS.

Application filed November 6, 1925. Serial No. 67,211.

My invention relates to pocket seals, and has for its object the production of a locking device for holding the seal closed when it is not in use. I have illustrated my invention as applied to a pocket seal of the kind shown and described in patent to H. S. Folger, No. 836,108, issued November 20, 1906.

In the accompanying drawings

Fig. 1 is a side elevation, partly in section, of a pocket seal with my invention applied thereto;

Fig. 2 is a plan of Fig. 1; and

Fig. 3 is a perspective view of the locking device detached.

In the frame 10 is a plunger 11 provided with a head 12 which carries the movable member of the seal, the stationary member being supported on the frame. On the top of the plunger 11 is a plate 13, and in a recess in the frame is a spring 14 which is located under a rearwardly projecting part of plate 13. The action of the spring is to elevate the plunger and thus open the seal.

Located in the frame 10 over the plunger 11 is a transverse pin 15, on which is pivoted the head 22 of hand lever 16. On the under part of head 22, and near the pivot 15, is a cam 17 which engages the top of plate 13 and serves to depress the die head 12 against the action of spring 14 when the lever 16 is depressed. The cam is so constructed that when hand pressure is relieved on lever 16, the spring opens the seal and the lever moves from full-line to dotted line position.

As shown in Fig. 2, the pivoted end 22 of the lever is located in a fork in the frame, said fork consisting of lugs 18 and 19. In front, the metal between these forks forms a shoulder 20, and on the head 22 of the lever is a corresponding shoulder 21. When the spring acts to raise the lever 16, the degree of elevation is limited by shoulder 21 coming into contact with shoulder 20.

When the lever is depressed to close the seal, there is an open space between these two shoulders.

The width of the head 22 is a little less than that of the space between the lugs 18 and 19, and in the remaining part of this

space is a piece of sheet metal 23 having a slot 24 thru which the pivoting pin 15 passes. In front, the piece 23 has a projection 25 bent at right angles to the part in which is located the slot 24. At the rear end, the piece 23 has a small projection bent in the opposite direction and serving as a finger piece for sliding the body 23 back and forth on the pivoting pin 15.

The projection 25 has a vertical depth 60 equal to the space between the shoulders 20 and 21 when the lever is depressed, and the construction is such that this projection may be pushed into this space to hold the seal closed when such depression occurs. A forward pressure on the projection 26 will move the projection 25 out of the space between shoulders 20 and 21, whereupon the spring 14 will open the seal and raise the lever until shoulder 21 contacts with shoulder 20. 70

From the above description it will be seen that the part illustrated in Fig. 3 is a locking device for holding the seal of Fig. 1 in closed position. To lock the seal, it is only necessary to close it and press the projection 75 25 into the space between shoulders 20 and 21. The force required is simply that necessary to move the weight of the locking piece 23. When in this condition, the action of the spring moves the lever to grip 80 and hold the projection 25, which means that the seal is held locked by the force which opens it when the locking piece is pushed forward.

What I claim is:

In a pocket seal, a frame having a pivoting pin and a shoulder serving as a stop, an operating lever pivoted upon the pin and having a shoulder arranged to engage the shoulder on the frame, a spring supported 90 by the frame and acting upon the lever so as to raise it and bring said shoulders into contact with each other, and a locking device made in the form of a slide guided upon said pin and a part of said frame, said locking device having a lateral projection arranged to be inserted between said shoulders when the operating lever is manually depressed.

MATT M. COREY.
